UNITED STATES PATENT OFFICE.

NELLIE F. CONWAY, OF BUFFALO, NEW YORK.

DESIGN FOR A HAT.

SPECIFICATION forming part of Design No. 31,915, dated November 28, 1899.

Application filed October 31, 1899. Serial No. 735,428. Term of patent 3½ years.

To all whom it may concern:

Be it known that I, NELLIE F. CONWAY, a citizen of the United States, residing at Buffalo, in the county of Erie and State of New York, have invented and produced a new and original Design for Hats, of which the following is a specification, reference being had to the accompanying drawings, forming a part thereof.

10 This design relates to the ornamentation and configuration of crocheted or knit hats.

In the accompanying drawings, Figure 1 is a perspective view of a hat embodying my design, and Fig. 2 is a transverse section of

15 the same.

The leading feature of my design consists of a hat having a knit or crocheted rim of ruching and having a crown provided with ribs having the form of polygons arranged

20 one within another.

Referring to the drawings, A represents the crown of the hat.

a represents the ribs of the crown, which form the polygons arranged one within another and which give the crown a polysec- 25 toral appearance.

B represents the rim of the hat, which consists of ruching.

What I claim is—

The design for a hat, substantially as herein shown and described.

Witness my hand this 26th day of October, 1899.

NELLIE F. CONWAY.
